SAFETY RAZOR BLADE

David Strauss, Rochester, N. Y., assignor of one-half to Julius Simon, Rochester, N. Y.

Application November 22, 1939, Serial No. 305,727

3 Claims. (Cl. 30—351)

The present invention relates generally to blades for safety razors, and more particularly to a blade for a safety razor of the character described and claimed in my copending application, filed of even date herewith, Serial No. 305,726, in which provision is made for a blade slidable on its seat under spring tension, permitting its yielding movement toward and away from the guard.

My above application specifically outlines a certain construction wherein the formation of the blade itself definitely enters, to a certain extent into the effective cooperation of the razor and the blade which promotes the yielding of the blade under spring tension with respect to the guard of the razor, more especially in view of the desire for a blade which might be of either the single or the double edge type.

The present application is directed particularly to the construction of the blade, and in the following description thereof particular reference is directed to the accompanying drawing, illustrating the best mode thus far devised for carrying the invention into practical effect, and forming a part of this specification.

In the drawing,

Figure 1 is a perspective view of the blade, showing the same of the double edge type.

Figure 2 is a plan or face view of the blade of Figure 1.

Figures 3 and 4 are vertical transverse sections taken through the blade respectively on lines 3—3 and 4—4 of Figure 2.

Figure 5 is a longitudinal sectional view taken on line 5—5 of Figure 2.

Figure 6 is a plan or face view of another modified form permitting of a single or double edge.

Referring now to these figures, the blade is generally indicated at 10 in Figures 1 to 5, inclusive, where it appears of the double edge type, having cutting edges 11 and 12 along its opposite longitudinal edges.

At an approximately central point the blade is provided with an opening 13 therethrough, preferably slightly elongated in a direction parallel to the transverse axis of the blade.

At its opposite ends and intermediate its cutting edges 11 and 12, the blade is provided with longitudinal recesses 14 arranged in parallel relation in pairs and spaced apart in each pair so as to form oppositely longitudinally extending fingers 15 whose outer ends terminate coincident with the ends of the blade.

It will be noted that the recesses 14 are of substantial depth and that by reason thereof the fingers 15 are likewise of substantially length, the recesses being so related to the blade as a whole as to leave the fingers 15 comparatively thin and in the plane of the body of the blade whereby they may yield toward either of the cutting edges 11 and 12. It is to be understood that being thus thin and flexible, adapting the same to yield toward either longitudinal edge of the blade, one or both of which may be cutting edges, these fingers, being an integral part of the blade itself are naturally resilient since resilience is a quality of the entire blade, so that the fingers, if engaged at their outer free ends on the supporting surface of a razor with respect to which the remainder of the blade may shift in the plane of its body, it is obvious that a blade will be yieldingly held.

Moreover, since the flexible resilient fingers 15 at opposite ends of the blade are located equidistant from the two longitudinal edges of the blade, the latter will be plainly reversible and may be either of the single or double edged type.

In Figure 6 I have shown a blade 10^b in which, by means of slotted openings 14^b, a pair of prongs or fingers 15^b are formed which extend inwardly toward one another with their inner free ends spaced apart. In this form, as in the other form, the prongs or fingers lie wholly within the limits of the blade both as regards its outer edges and its body plane.

In the operation of either of the forms of the invention as described above, the ends of the spring fingers 15 or 15^b as the case may be are rigidly clamped between a pair of lugs or other holding means formed on the blade holder and the remainder of the blade is allowed to "float" (so to speak) on the surface of the holder face plate in such a manner that when resistance is encountered by the forward edge of the blade, the blade will yield against the action of the spring fingers 15 or 15^b. Thus, in a measure, the blade by its movements will simulate the touch of a barber who, in using a straight edge razor, allows his forefinger to be held against the thick edge of the blade in order to judge, through his sense of touch, the proper degree of force which should be applied to the blade when a change in shaving resistance is encountered.

What is claimed is:

1. A thin, flat, generally rectangular, spring-steel blade for safety razors having a centrally disposed opening in the body thereof, said blade

being formed with longitudinally extending opposed and aligned fingers projecting inwardly toward the center of the blade from opposite sides of said opening, said fingers being spaced from each other and for their major portions being spaced from adjacent portions of the edges of said opening and lying in the plane of the body of the blade, said fingers being sufficiently narrow as to be capable of flexing in the plane of the blade and of returning to their normal position due to their inherent resiliency.

2. A thin, flat, generally rectangular blade for safety razors formed of resilient material and having formed therein slotted recesses extending longitudinally inwardly from its opposite ends 15 and arranged in pairs forming oppositely extending integral fingers lying within the outer con-

fines of the blade and in line with the longitudinal center-line of the latter, said fingers being sufficiently narrow as to be capable of flexing in the plane of the blade and of returning to their normal position due to their inherent resiliency.

3. A thin, flat, generally rectangular blade for safety razors formed of resilient material, said blade being formed with longitudinally extending aligned fingers, said fingers being spaced from each other and for their major portions being spaced from adjacent portions of the blade and lying in the plane of the body of the blade, said fingers being sufficiently narrow as to be capable of flexing in the plane of the blade and of returning to their normal position due to their inherent resiliency.

DAVID STRAUSS.
